KNITTING MACHINE STOP MOTION

Ralph W. Shepard, Worcester, Mass.

Application March 9, 1954, Serial No. 414,966

4 Claims. (Cl. 66—165)

This invention relates to a stop motion for a knitting machine and has for its primary object to arrest the operation of the machine when a needle contacts a yarn guide and thus to avoid the production of faulty fabric and injury to the mechanism.

Another object is to facilitate the conversion of an ordinary knitting machine into one equipped with this improved stop mechanism with but a minimum of expense.

The above and other objects may be attained by employing this invention which embodies among its features means connected to the yarn guides and to the needles of a conventional warp knitting machine and operatively connected to the energy supply means of the knitting machine for interrupting the supply of energy to the energy supply means when a yarn guide deviates from its path of movement to an extent that it contacts an adjacent needle, or a needle deviates from its path of movement to an extent that it contacts an adjacent yarn guide.

Other features include a row of longitudinally spaced yarn guides carried by the guide bar for movement therewith and being electrically isolated from the guide bar and electrically connected to one terminal of a signalling circuit, and the other terminal of the signalling circuit being connected to a row of needles mounted adjacent the guide bar for movement adjacent the guides, and means operatively connected to the driving motor of the knitting machine and electrically connected to the guides and to the needles for arresting the supply of energy to the motor when a needle contacts a yarn guide or a yarn guide contacts a needle.

In the drawings:

Figure 1 is an enlarged diagrammatic view of a needle bar and of a guide bar showing the guides carried by the guide bar and the needles carried by the needle bar electrically connected to a signalling circuit which controls the supply of electrical energy to the drive motor;

Figure 2 is an enlarged face view of one of the guide supporting blocks;

Figure 3 is an edge view of the guide supporting block;

Figure 4 is a horizontal sectional view taken substantially on the line 4—4 of Figure 2;

Figure 5 is a diagrammatic view illustrating the bearded needle with the yarn guides in one position relative thereto;

Figure 6 is a view similar to Figure 5, showing the needle and yarn guides in another position;

Figure 7 is a view similar to Figure 6, showing the needle and yarn guides in still another position;

Figure 8 is a diagrammatic view showing the yarn guides in one position relative to a latch needle;

Figure 9 is a view similar to Figure 8, showing the yarn guides in a different position relative to the latch needle; and

Figure 10 is a fragmentary sectional view taken substantially on the line 10—10 of Figure 2.

Referring to the drawings in detail, a needle bar 10 carries a group of clamp plates 12 which support knitting needles 14 in a position to extend in spaced parallel relation from one edge of the needle bar. Carried by the machine to rock about its longitudinal axis and to shog in a longitudinally extending path adjacent the needle bar 10 and in spaced parallel relation thereto is a guide bar 16 upon which the yarn guides, to be more fully hereinafter described, are supported for movement in closed paths which encompass the axes of the needles. Mounted in juxtaposed relation on the guide bar 16

2

are blocks 18 of electrically conductive material carrying adjacent their edges which lie adjacent the needle bar 12 longitudinally spaced yarn guides 20 which extend outwardly from the edge of the guide bar 16 adjacent the needle bar 10. Extending through each guide block 18 is an opening 22 in which is fitted a bushing 24 of nonconducting material, and carried by opposite side edges of the block 18 are pads 26 of nonconducting material which project beyond the side of the guide block 18 which is disposed adjacent the guide bar 16. Suitable attaching screws 28 extend through the bushings 24 to clampingly hold the guide blocks 18 on the guide bar 16, as will be readily understood upon reference to the drawings.

5 Bearing against each block 18 is a clip 30 having extending therethrough an opening 32 for the accommodation of the bushing 24 and carried by each clip is a spur 34 which is adapted to enter the adjacent block 18, as illustrated in Figure 10, to establish good electrical contact between the block and the clip. Carried by the clip adjacent one end thereof is a loop 36 which is adapted to encircle in electrical contact therewith a conductor 38. As illustrated in Figure 1, the conductor 38 extends through the loops 36 of the clips 30 carried by the respective blocks 18 on the guide bar 16 and is connected to one terminal of an electronic relay 40, the opposite terminal of which is connected through a conductor 42 to the needle bar 10. Thus, it will be obvious that when a guide 20 contacts a needle 14 or a needle 14 contacts a guide 20 during the operation of the machine, an electrical circuit will be established through the electronic relay, the output side of which is coupled through the medium of conductors 44 and 46 to an intermediate relay 48. The output side of the intermediate relay 48 is connected through the medium of connectors 50 and 52 to a motor control switch 54 through which electrical energy is supplied to the drive motor 56 of the machine.

In operation, it will be understood that as the guides 20 move in their predetermined paths during the normal operation of the machine adjacent the needles 14, the knitting operation will progress. Should either a needle, or a guide deviate from its normal path of movement to an extent that it contacts an adjacent yarn guide 45 or needle, respectively, an electrical circuit will be closed through the electronic relay to actuate the intermediate relay and the control switch 54 to open the control switch and interrupt the supply of energy to the motor 56. Such action will serve to arrest the operation of 50 the knitting machine so as to prevent the production of faulty fabric and also notify an attendant that the machine is out of adjustment. In this way, the attendant may adjust the machine before any serious damage is done to the instrumentalities which would entail a costly repair.

By using the stop mechanism, herein described, it is obvious that the production of faulty fabric and the necessity of expensive repairs to the mechanisms will be avoided.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

1. In a knitting machine having yarn guides which move in closed paths, needles which move in paths which extend within the closed paths, a prime mover operatively connected to the yarn guides and to the needles for moving them in their respective paths, means connected to the prime mover for supplying energy thereto, and means connected to the yarn guides and to the needles and operatively connected to the energy supply means for interrupting the supply of energy to the prime mover when a yarn guide deviates from its path of movement to an extent that it contacts an adjacent needle or a needle deviates from its path of movement to an extent that it contacts an adjacent yarn guide.
2. In a knitting machine having yarn guides which move in closed paths, needles which move in paths which

extend within the closed paths, means operatively connected to the yarn guides and to the needles for moving them in their respective paths, and means connected to the yarn guides and to the needles for arresting operation of the yarn guides and needles when a yarn guide deviates from its path of movement to an extent that it contacts an adjacent needle or a needle deviates from its path of movement to an extent that it contacts an adjacent yarn guide.

3. In a knitting machine having a guide bar, a row of longitudinally spaced yarn guides carried by the guide bar for movement by said guide bar in closed paths, said yarn guides being in electrical communication with one another but electrically isolated from the guide bar, a row of needles mounted adjacent the guide bar for movement in rectilinear paths which extend through the closed paths, said needles being in electrical communication with one another, drive means operatively connected to the guide bar and to the needles for moving them in their respective paths, electrically actuated means operatively connected to the drive means which, upon energization, interrupts the supply of energy thereto, and said electrically actuated means being electrically connected to the yarn guides and to the needles for energization when a yarn guide deviates from its path of movement to an extent that it contacts an adjacent needle

or a needle deviates from its path of movement to an extent that it contacts an adjacent yarn guide.

4. In a knitting machine an guide bar mounted to rock about a longitudinal axis and to shog in a longitudinally extending path, a needle bar mounted in spaced parallel relation to the guide bar, needles carried by the needle bar and extending toward the guide bar, yarn guide supporting blocks carried by the guide bar in electrically isolated relation thereto, yarn guides carried by the yarn guide supporting blocks and extending outwardly therefrom toward the needles for movement in closed paths which encompass the axes of the needles, a stop motion operative upon energization of a signalling circuit to arrest the operation of the machine, and opposite terminals of the signalling circuit being electrically connected to the needle bar and to the yarn guide supporting blocks whereby when contact is effected between a yarn guide and a needle the signalling circuit will be energized and the operation of the machine will be arrested.
